Primary Examiner—Charles A. Rademaker(74) *Attorney, Agent, or Firm*—Foley & Lardner LLP(57) **CLAIM**

We claim the ornamental design for a material trimmer, as shown and described.

DESCRIPTION

FIG. 1 is a perspective view of a material trimmer showing our new design;

FIG. 2 is a top view thereof;

FIG. 3 is a rear side view thereof;

FIG. 4 is a right view thereof;

FIG. 5 is a front side view thereof;

FIG. 6 is a left view thereof; and,

FIG. 7 is a bottom view thereof.

The broken lines shown in the drawings are included for the purpose of illustrating environmental structure and form no part of the claimed design.
